Primary Examiner — Keli Hill(74) *Attorney, Agent, or Firm* — Knobbe, Martens, Olson & Bear, LLP(57) **CLAIM**

The ornamental design for a video game console, as shown and described herein.

DESCRIPTION

FIG. 1 is a top, front perspective view of a video game console;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the figures are for the purpose of illustrating unclaimed portions of the video game console and form no part of the claimed design.

1 Claim, 7 Drawing Sheets(56)
